Des. 231,118
Patented Apr. 2, 1974

231,118

PORTABLE LIGHT

Charles R. Moore, 1615 Merrifield,
Mishawaka, Ind. 46544

Filed Apr. 28, 1972, Ser. No. 248,788

Term of patent 14 years

Int. Cl. D26—02

U.S. Cl. D48—24 R

Fig. 1

Fig. 2

Fig. 3

Fig. 4

Fig. 5

Fig. 6

Fig. 7

FIG. 1 is a perspective view of a portable light embodying my new design;

FIG. 2 is a side elevational view of the portable light on a reduced scale;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of the modified form of the portable light embodying my new design.

The front of the second embodiment is identical to the front of the first embodiment as best shown in FIG. 3.

I claim:

The ornamental design for a portable light, as shown and described.
